EX

OR D 15.248

D15248 Aug 12, 1884

UNITED STATES PATENT OFFICE.

FERDINAND MASSET, OF CHICAGO, ILLINOIS.

DESIGN FOR A MIRROR-FRAME.

SPECIFICATION forming part of Design No. 15,248, dated August 12, 1884.

Application filed June 17, 1884. Term of patent 3½ years.

To all whom it may concern:

Be it known that I, FERDINAND MASSET, a citizen of the United States of America, residing at Chicago, in the county of Cook and State of Illinois, have invented certain new and useful Improvements in Designs for Mantel-Mirrors, of which the following is a specification, reference being had therein to the accompanying drawing.

10 My design relates to mantel-mirror frames, for the details of which reference is made to the accompanying illustration, wherein all the features are clearly portrayed.

The main features of the design are in the 15 general outlines of the frame, and in the ornamentation of the top and side rails thereof. There is a central mirror, A, suitably mounted, and upon each side thereof two smaller mirrors, B, above and below each of which is 20 a small bracket, C. To the side of brackets C are uprights D, ornamented as follows: At the lower end of each is a knob, a, at the cen-

ter of each an enlarged circular section, b, and at the upper end of each an enlarged ornamented section, c. The top rail is marked E, 25 and is ornamented with a bar, d, which is arch-shaped throughout the enlarged portion E' of said rail, and horizontal throughout the remaining portions of said rail. In each upper corner of section E' is suitable scroll-work, e, and below bar d in said section E' suitable lines or ornamentations, as at f.

What I claim is—

1. The design for a mantel-mirror frame, as shown.
2. In a mirror-frame, the design for top rail, E E', as shown.

In testimony whereof I affix my signature in presence of two witnesses,

FERDINAND MASSET.

Witnesses:

M. J. CLAGETT,
HENRY ALLEN.
